UNITED STATES PATENT OFFICE.

HENRY TOWNSEND WORRALL, OF CHELMSFORD, ENGLAND.

LOCKING DEVICE FOR ELECTRIC LAMPS.

1,137,177.

Specification of Letters Patent. Patented Apr. 27, 1915.

Application filed December 26, 1913. Serial No. 808,763.

To all whom it may concern:

Be it known that I, HENRY TOWNSEND WORRALL, a subject of His Majesty the King of England, residing at 202 Springfield road, Chelmsford, in the county of Essex, Kingdom of England, have invented a certain new and useful Locking Device for Electric Lamps, of which the following is a specification.

10 This invention relates to certain improvements in and connected with a locking device in conjunction with a removable lamp cap or like member whereby simple means are established for effectively locking in-
15 candescent electric lamps or the like of the bayonet type to their respective holders or sockets. The principle herein described cur- tails any pecuniary loss, inconvenience and annoyance caused through lamps being
20 stolen or wrongfully removed by unauthor- ized persons. In large establishments se-
rious and unsuspected losses are often in-
curred from the above mentioned cause.
The principle I adopt while retaining most
25 of the well known features of the bayonet
type lamp or other fitting, makes a slight
increase as regards dimensions absolutely
necessary but this increase is of no impor-
tance whatever, seeing that in most of the
30 modern metal filament lamps the bulbs
have enormously increased in size while the
lamp sockets have consistently remained the
same, the bulb and the socket as at present
constituted being greatly out of proportion
35 to each other.

The invention is hereinafter described
with reference to the accompanying draw-
ings in which:—

Figure 1 is an elevation of the porcelain
40 insulator of the lamp holder or socket show-
ing the locking shaft fitted thereto; and
Figs. 2 and 3 are a top and an underneath
plan view, respectively of said insulator.
Fig. 4 is a plan of the top section of the
45 two-part lamp cap; and Fig. 5 is an elevation
of same. Fig. 6 is an elevation of the
bottom section of the lamp cap. Fig. 7 is
an elevation showing the two sections of the
lamp cap assembled. Figs. 8 and 9 are
50 views of one of the fastening staples. Fig.
10 is a sectional elevation of the complete
device.

Putting my invention into practice I fix
a concentric locking shaft *a* to the porcelain
55 insulator *b* of the lamp-holder or socket,
which locking shaft is self-centering, self-

alining and entirely insulated from the
plunger contacts *c*. It is composed prefer-
ably of flexible metal, is cross slotted as at
d to form three, four or any number of con-
centric locking jaws *e*, and is made to fit
loosely in a suitable hole *f* provided in the
center of the porcelain insulator *b* and to
bear on a shoulder *g*. A collar *h* is fitted
on the upper end of the shaft, and the shaft
is then expanded as shown at *i*. If mounted
in this way the shaft will have sufficient
freedom to make it self-centering and self-
alining to the insulated locking cylinder or
tube *j* in the lamp cap.

70 The insulated locking cylinder *j* is sim-
ply a plain cylindrical tube open at both
ends and formed with an external rib *k*
projecting at a point about half its length,
which rib prevents any displacement of the
75 cylinder in the insulation *l* of the section *l*
of the cap.

The lamp cap is composed of two distinct
parts or sections namely the upper section *l*
and the lower section *m*, adapted to be de-
tached one from the other. The upper sec-
tion *l* carries, in addition to the locking cyl-
inder *j*, contacts which may be of the ordi-
nary type. I prefer, however, to use the
pattern shown at *n* as being the more suit-
able for this particular device. It will be
noticed, by reference to Figs. 4, 5 and 7,
80 that the usual radial lamp attaching pins on
the upper section of the cap are dispensed
with. Instead of such pins, which are al-
ways liable to become loose, to break or fall
out, I bring into use one or more concave
85 indents *o*, and these indents, as will be easily
understood, slide within corresponding in-
dents in the lamp-holder. However, I have
90 found that one indent only, if well made, is
quite sufficient to prevent the lamp being
twisted around when locked in the holder,
and of course the usual pins and slots may
take the place of indents if preferred.

95 The lower section *m* of the cap carries the
lamp bulb *m'* to which it is cemented in the
usual manner. Both sections *l* and *m* are
spun, pressed or formed with extension
100 pieces *p* of slightly different diameters, and
the extension piece of the section *l* is of such
diameter as to permit of a good sliding fit
being made on the extension piece of the sec-
tion *m* thus forming a telescopic like junc-
105 tion as in Fig. 7. For the purpose of at-
taching the two sections together two or
more small holes *q* are punched through the

said junction equi-distant apart, and suitable fasteners or staples *r*, fashioned as in Fig. 8, are inserted in the holes and then pressed flat as in Fig. 9. The upper and lower sections now become securely united 5 and form a complete cap as in Fig. 7. If one or the other of the cap sections *l* and *m* was twisted radially, *i. e.*, one independently of the other, undue lateral strain would fall on the soft metal fasteners *r*, and these in turn would have a tendency to straighten out and become loose. To prevent this happening coöperating indents *s* and *s'* are formed in the peripheries of the cap sections 10 *l* and *m*, respectively. Here again a slot and pin may be used if desired.

The fasteners or staples *r* are stamped out and bent, to shape as in Fig. 8 and are made of soft sheet brass of about the same gage 20 as the cap sections, and although made of such slender metal they are amply strong enough when fixed to withstand any pressure brought to bear on them edgewise.

Fig. 7 shows an exterior view of a complete cap ready to have a bulb cemented thereto.

To put a new lamp in the lamp-holder, assuming the lamp and the lampholder are fitted with the parts now fully described, all 30 that is required is a straight push into the holder and this causes the insulated concentric locking shaft *a* on the holder to travel the entire length of the insulated locking cylinder *j* in the lamp cap, resulting in an insulating automatic lock being made in the interspace of the lamp cap as shown in Fig. 35 10. Should any attempt now be made to remove the lamp *m'*, locked in the manner aforesaid, from the holder it will be rendered practically useless for all intents and 40 purposes as described hereafter.

When a defective lamp requires removal the soft metal fasteners or staples *r* are withdrawn from the sectional lamp cap *l* and *m*. 45 This leaves the section *m* of the cap free to be detached from the section *l*, by a slight downward pull, the said pull breaking the current conductors *m*² inside the lamp cap. The current conductors *m*² are constructed 50 so that they have their weakest breaking points situated near to the plunger contacts *c* and this arrangement prevents any possibility of a short circuit taking place during the said process of extraction. The 55 lower section *m* of the cap being now removed the upper section *l* may be unlocked by pressing together the jaws *e* of the insulated locking shaft *a* and the plunger contacts *c* of the lamp-holder, being in a state 60 of depression, will eject the section *l* of the cap from the holder. The holder is now ready to receive a new lamp. No tool, key or switch is required and the locking shaft *a*, being perfectly insulated from the live 65 plunger contacts *c*, may be handled by the

most inexperienced person with absolute safety.

What I claim as my invention and desire to secure by Letters Patent of the United States is:—

1. A lamp having a cap comprising upper and lower detachably connected sections, a plug provided with contacts and a locking cylinder arranged in said upper section, the filaments of said lamp extending through 70 said lower section and secured at their ends to said contacts, in combination with a socket provided with contacts and a locking shaft for engagement with said plug contacts and locking cylinder respectively, said locking 75 means being capable of being released only upon separation of said upper and lower members, substantially as described.

2. In a device of the class described, a lamp provided with a cap formed of upper 80 and lower detachably connected sections, said upper section having a plug provided with a central opening and electrical contacts, a pair of conductors connecting to said contacts and passing through said lower section 85 to said lamp; in combination with a socket provided with electrical contacts and an outwardly extending centrally disposed locking shaft for engagement with said plug contacts, and said opening respectively, the 90 said locking shaft being capable of being released only upon separation of said upper and lower members, and the sides of said cap and socket being provided with coöperating indents for properly alining said contacts and preventing rotation of said lamp 95 and socket, substantially as described.

3. In a device of the class described, the combination of a lamp and socket, said lamp being provided with a cap formed of upper 100 and lower detachable sections, said upper section having a plug provided with contacts and a centrally disposed locking cylinder 105 communicating with said lower section, the filaments of said lamp extending through 110 said lower section and connected to said contacts, said socket being provided with contacts and an outwardly extending shaft, said shaft being adapted to be extended through said cylinder and having spring shoulders 115 at its outer end for snapping engagement behind said plug, and means for securing said upper and lower sections together, substantially as described.

4. In a device of the class described, the combination of a lamp and a socket, said lamp being provided with a cap comprising upper and lower separable sections, said upper section having a plug provided with contacts, current conductors, connected to 120 said contacts and passing within said lower section to said lamp, means for securing said upper and lower sections together, contacts on said socket for engagement with the contacts on said plug when the said cap is in- 125 130

serted within said socket, and coöperating means within said socket and lamp for holding the same together, the said means being accessible for releasing the socket and lamp only upon separation of said upper and lower members, substantially as described.

5. In a device of the class described, a lamp and a socket, said lamp having the usual current conductors and being provided with a cap adapted to fit within said socket, said cap comprising a pair of interlocking separable sections, one of said sections being provided with a centrally disposed locking cylinder and also a pair of contacts to which the ends of said current conductors are secured, and the other of said sections being secured at one end to said lamp and supporting said first named section at its opposite end spaced from said lamp, said socket having contacts and a centrally disposed outwardly extending locking shaft for coöperation with the contacts and locking cylinder respectively of said first named section, the said shaft and locking cylinder being so arranged as to be capable of being released from engagement with each other only upon separation of said sections, substantially as described.

6. In a device of the class described, a lamp having a cap adapted to engage within a socket, said cap comprising upper and lower sections, said upper section being provided with a plug having contacts, said upper and lower sections having interfitting flanges provided with registering openings, locking members for coöperation with said openings for holding said sections assem-

bled, the filament of said lamp extending through said lower section and secured to said contacts, whereby upon separation of said members the said filament will be broken, and said plug being provided with an opening extending therethrough to receive a locking device, substantially as described.

7. In a device of the class described, a lamp and a socket, said socket being provided with a centrally disposed outwardly extending locking shaft, said lamp having a cap comprising upper and lower sections, said upper section being provided with a plug having contacts and a centrally disposed locking cylinder communicating with said lower section for the reception of said locking shaft, said upper and lower sections having interfitting flanges provided with registering openings, locking members for coöperation with said openings for holding said sections assembled, the filament of said lamp extending through said lower section to be secured to said contacts, whereby upon separation of said sections the said filament will be broken and coöoperating locking means upon said locking shaft and said locking cylinder releasable only upon separation of said upper and lower members, substantially as described.

In testimony whereof I have signed this specification in the presence of two subscribing witnesses.

HENRY TOWNSEND WORRALL.
